UNITED STATES PATENT OFFICE

2,529,040

VENTILATING FAN FOR WINDOWS

Hackley Morrison, Houston, Tex., assignor, by
mesne assignments, to Hackley Morrison, Jr.

Application August 3, 1945, Serial No. 608,772

3 Claims. (Cl. 98—94)

1

This invention relates to ventilating fans and more particularly to fans adapted to be mounted within the space normally occupied by the lower sash of an ordinary two-sash window.

In the use of fans of this character, it is desirable to employ fans having a blade circle as nearly as possible equal to the width of the window, in order to secure maximum efficiency.

Most windows, however, as ordinarily constructed, have a width somewhat greater than the distance between the sill and the lower edge of the upper sash when fully open, and for this reason, if a fan having a blade circle substantially equal to the width of the window be employed, and the fan be set, as is usually the case, to just clear the window sill, then the upper part of the blade circle will overlap the lower edge of the open bottom sash, thus decreasing the efficiency of the fan.

It is therefore one object of the present invention to provide a ventilating fan for windows such as above described, so constructed as to reduce to a minimum the extent of overlapping of the lower edge of the sash by the blade circle.

Stated in another way, an object of the invention is to devise means for so mounting the fan as to support the fan shaft at a point substantially midway between the sill and the lower edge of the sash, so that the overlapping of the blade circle is substantially equally divided between the sill and the lower edge of the sash.

Ventilating fans of the character referred to are usually mounted in a rigid frame, and it is customary to support this frame on the window sill itself. Where a substantially square frame is employed, and where the width of the window is greater than the distance between the sill and the lower edge of the sash, this results in the fan shaft being disposed at a point nearer the edge of the sash than the sill, thus producing an undesirable overlap of the blade circle on the sash.

In order to avoid this, while employing the usual square frame, I contemplate the provision of means for supporting this frame in such a manner that its lower portion depends below the sill. In this way, I am enabled to bring the fan shaft down to a point where it lies substantially midway between the sill and the lower edge of the sash, thus dividing the overlap between the top and bottom of the blade circle, whereby the area of overlap is substantially reduced.

My invention is particularly applicable to fans of the type in which a relatively small motor is mounted in one corner of the frame and drives the fan by means of a belt and pulleys. Another ob-

2

ject of the invention is therefore to provide a construction in which the fan frame comprises a portion depending below the sill, and in which the motor is housed within this depending portion.

A further object of the invention is to devise adjustable means for supporting the fan frame on the window sill, whereby the frame may be adjusted to any one of several different vertical positions, as required.

A still further object of the invention is to devise simple and efficient means for anchoring the fan frame to the window casing, this anchoring means being so constructed that the same frame may be applied to windows varying considerably in width.

Yet another object of the invention is to provide a fan frame of improved construction which shall be exceptionally rigid and free from vibration.

20 In order that the invention may be readily understood, reference is had to the accompanying drawings forming part of this specification and in which:

Fig. 1 is a perspective view of my improved 25 ventilating fan as it appears when mounted in position on a window sill.

Fig. 2 is an edge elevation thereof on an enlarged scale, parts being broken away.

Fig. 3 is a fragmentary transverse section substantially on the line 3—3 of Fig. 2, looking in the direction of the arrows.

Fig. 4 is a front elevation on a somewhat larger scale of the fan shown in Fig. 1, the guard being omitted for the sake of clearness, and

35 Fig. 5 is a transverse section substantially on the line 5—5 of Fig. 4, looking in the direction of the arrows.

Referring to the drawings in detail, A designates the usual window casing or trim and B indicates the usual sill. The lower sash is indicated at C.

40 My improved fan comprises a rectangular frame 1 consisting of a pair of spaced parallel baffle plates 2, having outturned marginal flanges 3 secured to a rim member 4. This projects laterally beyond the baffle plates and is provided with an inturned peripheral flange 5 on each side. Thus the frame is of substantial thickness, from front to back. Extending through the registering openings in the baffle plates 2, and bridging 45 the space between said plates, is an annular member or funnel 6 having peripheral radial flanges 6a overlapping and secured to the edges of the baffle plates as best shown in Fig. 3.

45 The construction of this fan frame, including 50 the baffle plates and funnel, is generally similar to

that shown and described in my prior Patent No. 2,385,152, dated September 18, 1945, but differs therefrom in certain details.

The fan itself is shown as comprising four blades 7 carried by a hub or spider secured to a shaft 8, this shaft being journaled in bearings carried by cross bars 9 attached to brackets 10 secured to the frame 1.

A grille or guard 12, consisting of woven wire, expanded metal or the like, mounted in a frame, is preferably provided on the inside of the window to prevent accidental contact with the fan, and this is mounted on brackets 11 carried by the frame 1, as shown in Figs. 1 and 4.

Adjacent one corner of the frame 1, the baffle plates 2 are cut away as shown at 13 in Fig. 4 to provide a pocket in which is mounted a suitable electric motor 14, having an extension cord 14a by which it may be connected with a source of current. About a pulley on this motor shaft and a suitable pulley 16 on the fan shaft, runs an endless belt 15 by which the fan is driven, as in my above mentioned prior co-pending application.

Referring now more particularly to Figs. 1 and 2, it will be seen that the lower part of the frame 1, adjacent the side or face which fits against the window, is cut away or notched out through part of its thickness as indicated at 17, to accommodate the sill B and a vertically adjustable bracket 18 is secured to each side of the frame adjacent the notched out portion, to constitute means by which the frame is supported on the sill. The bracket 18 has a series of vertically spaced holes 19, and a pair of similarly spaced holes are formed in the frame, so that when any two of the holes 19 are brought into registry with the holes in the frame, screws or bolts 20 may be passed through the registering holes and the bracket 18 secured in any desired position relative to the frame.

The lower end of the bracket 18 is bent at right angles to form a foot 21 as shown in Figs. 3 and 5, and a rubber cushion 22 is preferably attached to the lower side of this foot so that it may rest upon the sill as shown in Fig. 2.

It will now be understood, by reference to the drawings, that the frame 1, which is preferably substantially square, is of a width somewhat greater than the width of the window, with the result that the frame overlaps the window casing A as clearly shown in Figs. 4 and 5. This is in contrast to the usual method of making the frame of adjustable width and attempting to fit it inside of the window frame. In my improved construction the frame is entirely rigid, and, because it is constructed to overlap the window casing, may be used with different windows which vary considerably in width.

An important feature of my invention is the improved means for anchoring the frame in position on the window. This improved means, as best shown in Fig. 2, comprises a tie rod 23 having a hook or the like at one end, adapted to fit into a hole 24 in the rim 4 constituting the thick edge of the fan frame, and having at its other end an eye through which a screw 25 may be passed into the edge of the window casing A. The rod 23 is formed in two sections connected by a turn buckle 26, so that its length may be varied as desired. It will be noted that the hole 24 in which the tie rod engages is remote from the face of the frame abutting the window casing and that the other end of the tie rod is attached to the window casing at a point spaced

laterally from the edge of the frame, so that the tie rod extends diagonally from the frame to the casing, as shown in Fig. 1. One purpose of this is to afford a space in which the turn buckle may be freely manipulated.

5 In mounting my improved fan in position on a window, all that it is necessary to do is to set the rubber cushions 22 on the window sill, as shown in Fig. 2, and then anchor the frame to the window casing by means of the tie rods 23. 10 Only a single such tie rod is required at each lateral edge and this should be spaced somewhat below the top of the frame as shown.

Cushions or pads of sponge rubber or the like 15 as indicated at 27 are preferably interposed between the frame 1 and the window casing, so that, when the tie rods are placed in position, and the turn buckles 26 screwed up tightly, the entire fan frame will be firmly secured in position. 20 Furthermore, the presence of the rubber cushions or pads 22 and 27 afford a resilient mounting which will absorb vibrations and render the fan exceptionally quiet in operation.

Referring to Fig. 4, the top of the sill is indicated at b and the lower edge of the sash C, 25 fully opened, is indicated at c. From this figure it will be seen that the amount of overlap of the blade circle with respect to the top of the sill and lower edge of the sash respectively, is substantially the same, and that this overlap in 30 each case is relatively small. In other words, the fan shaft 8 is located substantially midway between the top b of the sill and the bottom c of the sash.

35 If the lower side of the frame 1 rested directly on the sill, as has been the usual prior practice, the fan shaft would be located much nearer the edge c of the sash than the sill, with the result that there would be a relatively large overlap of the blade circle on the sash, and the area of this overlap would obviously be much greater than the aggregate of the areas of the relatively small upper and lower overlaps in my improved design.

40 It will therefore be appreciated that although I employ a square frame, and although I preserve the advantage of a blade circle having a diameter substantially equal to the full width of the window, I achieve the above mentioned 45 centering of the fan shaft and equalizing of the upper and lower overlap areas by the expedient of notching out the frame as shown in Fig. 2 so that the lower portion thereof depends below the sill, in contrast to resting on it. Moreover, it will 50 be observed that the motor 14 is housed in this 55 depending portion of the frame, and lies below the sill.

From the foregoing it is thought that the many 60 advantages of my improved arrangement over what has been the usual practice will be readily understood and appreciated by those skilled in the art.

What I claim is:

65 1. A window fan comprising a rectangular frame, a fan centrally mounted in said frame and having a diameter greater than the distance between the window sill and lower edge of the bottom sash when fully open, but no greater than the width of the window opening and means for supporting said frame on the window sill in such position that the blade circle overlaps said sill and the lower edge of said sash to substantially the same extent.

70 2. A ventilating fan for windows having a 75 width somewhat greater than the distance from

the sill to the lower edge of the bottom sash when full open, the blade circle of said fan being of a diameter substantially equal to the width of the window, and means for supporting said fan on the window sill in such position that said blade circle overlaps the sill and lower edge of the upper sash to substantially the same extent.

3. A window fan comprising a rectangular frame, a fan and motor mounted in said frame means for securing one face of said frame against the window casing, the lower portion of said frame adjacent said face being notched out throughout its width, and adjustable means mounted in said notched out portion and adapted to rest on the window sill for supporting said frame at any one of several different vertical positions.
